UNITED STATES PATENT OFFICE.

JAMES SIMPSON ISLAND, OF TORONTO, ONTARIO, CANADA.

APPARATUS FOR FORMING OXIDS OF NITROGEN.

1,082,529.

Specification of Letters Patent.

Patented Dec. 30, 1913.

Application filed December 27, 1911. Serial No. 668,086.

To all whom it may concern:

Be it known that I, JAMES SIMPSON ISLAND, a subject of the King of Great Britain, resident of the city of Toronto, county of York, Province of Ontario, in the Dominion of Canada, have invented certain new and useful Improvements in Apparatus for Forming Oxids of Nitrogen, of which the following is a full, clear, and 10 exact description.

The invention relates to improvements in an apparatus for forming oxids of nitrogen, as described in the following specification and illustrated in the accompanying 15 drawings that form part of the same.

The invention consists essentially in the novel construction and arrangement of parts, whereby a supply of oxy-nitrogen gas is passed through an electric arc flame to 20 effect the formation and fixation of the oxids of nitrogen.

The objects of the invention are, to reduce the cost of the production of oxids of nitrogen for commercial purposes, to increase 25 the efficiency and durability of such apparatus, and to devise an apparatus of very simple construction which may be operated with the minimum amount of attention.

In the drawings, Figure 1 is a vertical 30 cross sectional view through the electric arc forming portion of my device. Fig. 2 is a longitudinal vertical sectional view of the apparatus.

Like numerals of reference indicate corresponding parts in each figure.

Referring to the drawings, 1 is a tubular ring shaped member preferably formed substantially triangular shaped in cross section and having the apex 2 forming the inner 40 periphery, said ring forming the positive electrode.

3 are pipe openings arranged in the outer flat side 4 of the ring electrode 1 extending radially outward therefrom and adapted to 45 be connected to pipes leading from a suitable compressed air supply.

5 are a plurality of minute radial holes through the apex 2 of the ring 1 arranged close together and extending completely 50 therearound.

The ring 1 is rigidly supported within a cylindrical casing 6 close to one end there-

of, said casing having a lining 7 of silica, porcelain or other di-electric material.

8 is a shaft journaled in the bearings 9 arranged at each end of the casing 6.

10 is a driving pulley secured to one end of the shaft 8 outside of said casing.

11 is a rotor member rigidly secured to the shaft 8 and suitably insulated therefrom and forming the negative electrode. The rotor is formed of a hub 12 and radial arms 13 having segmental extensions 14 at their extremities, said arc shaped members being triangular shaped in cross section and 65 having their apexes 15 arranged outwardly and in central alinement with the apex of the ring 1. The apexes of the triangular shaped electrodes thus present opposing points.

16 is a binding post secured to the ring 1 and extending outwardly through the casing 6 and suitably insulated therefrom and connected to the positive lead from a suitable electric current supply.

17 is a binding post secured in one end of the casing 6 and connected to the negative lead from the electric current supply and having a brush 18 on its inner end engaging a flange 19 forming part with the hub 12 of the electrode 11.

20 is a cooling chamber arranged within the casing 6 and having a plurality of tubes 21 extending between the heads 22 and 23, said tubes forming cooling passages for the 85 oxidized gases.

24 are pipes connected to said cooling chamber through which a suitable cooling fluid is circulated.

The gases after passing through the cooling tubes are collected in a chamber 26 and are carried off through a suitable pipe 27.

The surfaces of the cooling compartment exposed to the gases are suitably glazed to prevent corrosion as is also the portion of 95 the shaft 8 within the casing.

In the use of this device, pipes leading to the tubular ring 1 are connected to a suitable compressed air supply and the terminals of the two electrodes are electrically connected to a high potential electric current supply, the ring forming the positive electrode. The rotor is operated by any suitable form of motor connected to the pul-

ley 10. The flow of electric current to the electrodes causes the formation of an electric flame between the apexes of the triangular shaped bodies. As the tendency of 5 the electric current is to find the path of least resistance the rotary movement of the segmental negative electrode causes the breaking of the electric arc as the gaps between the segments change their position in 10 relation to the inflowing current in the positive electrode. The result is that an annulus of electric flame is formed completely filling up the space between the adjacent peripheries of the two electrodes. It is a 15 well known fact that an electric flame consists of three zones, the inner zone having an exceptionally high temperature and that the inner zone emanates from the positive electrode. In this device the oxy-nitrogen 20 gas to be oxidized is conveyed to the tubular positive electrode and is forced out through the minute holes 5 in the apex directly into the center zone of high temperature thus 25 effecting the maximum oxidation of the nitrogen. It is very important that the gases be withdrawn as quickly as possible from the influence of the middle and outer zones to avoid the dissociation of the nitric oxids 30 formed in the inner zone and this result is accomplished to an exceptional degree in the present device.

The inflowing gas is projected at high velocity through the minute holes in the apex of the positive electrode and is thus forced 35 through the several zones by the continuous flow and as the negative electrode is formed in segments, the oxidized gases will enter the spaces between the radial arms where they come in contact with the angularly arranged blade-like arms and are driven laterally 40 into contact with the surfaces of the cooling chamber. The continuous inflow of gases of course, creates a pressure which causes the steady flow of the gases immediately 45 after passing through the electric flame to pass into contact with the cooling chamber but the fan like action of the rotary electrode accelerates this movement.

Another very important feature in the 50 arrangement of a rotary electrode within an encircling electrode is that the point from which the arc flame emanates is continuously changing and the arc is continuously broken by the rotary movement, thus obviating an 55 erosive effect on the points of the electrode. The constant change of the path of the electric circuit, due to the rotary movement, produces a very remarkable result in that the space between the two electrodes is filled 60 with a sheet of flame and as the air or other oxy-nitrogen gas is introduced through the hollow electrode immediately into the zone of highest temperature and around the complete circle of flame and is withdrawn

quickly therefrom, the result is a very great 65 increase in the oxids produced.

What I claim as my invention is:

1. In an apparatus for forming oxids of nitrogen, a hollow electrode formed in circle shape and having openings therein adapted 70 to project an annular sheet of oxy-nitrogen gas, and an electrode arranged in the plane of the projected gas and adapted to form an annulus of electric flame the central plane of which will be in the plane of the discharge of oxy-nitrogen gas.

2. In an apparatus for forming oxids of nitrogen, a hollow ring shaped electrode having inwardly directed discharge openings in its median plane adapted to project an 80 annular sheet of oxy-nitrogen gas, a rotary electrode arranged axially within said ring and adapted to create a zone of electric flame in the plane of the discharge from said ring electrode.

3. In an apparatus for forming oxids of nitrogen, a tubular ring shaped electrode connected with a suitable oxy-nitrogen supply and formed substantially triangular in cross section and having the apex turned inward and formed with a plurality of minute radial orifices, and a rotary electrode supported in central alinement with said ring and having segmental members presenting an edge outwardly in alinement with the 95 apex of said ring and adapted to create a zone of electric flame in the plane of the discharge of the oxy-nitrogen gas.

4. In an apparatus for forming oxids of nitrogen, a tubular ring shaped electrode 100 substantially triangular in cross section and having the apex turned inward and formed with a plurality of minute radial orifices in said apex, and gas inlet openings communicating with a suitable supply of oxy-nitrogen gas, and a rotor electrode adapted to rotate within said ring and having a plurality of radial arms formed with segmental ends substantially triangular shaped in cross 105 section.

5. In an apparatus for forming oxids of nitrogen, a tubular ring shaped electrode substantially triangular in cross section and having the apex turned inward and formed with a plurality of minute radial orifices in 110 said apex, a suitable supply of oxy-nitrogen gas communicating with said tubular ring, and a rotor electrode adapted to rotate within said ring and having a plurality of flat radial arms set in angular relation to the 115 axis of the rotor and forming fan blades, said arms having segmental outer ends presenting an edge outwardly.

6. In an apparatus for forming oxids of 120 nitrogen, a casing, a hollow ring shaped electrode arranged adjacent to one end of said casing and having inlet openings connected with a compressed gas supply and having

minute discharge openings in its inner side, a shaft journaled in said casing and extending through said ring, a rotary electrode secured to said shaft and having radial arms with arc shaped extremities, and a tubular cooling chamber arranged within said casing adjacent to said electrodes.

Signed at the city of Toronto, county of York, Ontario, Canada, this 20th day of December, 1911.

JAMES SIMPSON ISLAND.
